UNITED STATES PATENT OFFICE

2,246,056

SEWER OPENER

Lewis G. McKenzie, Columbus, Ohio, assignor of
one-half to Henry Maess, Columbus, Ohio

Application February 3, 1938, Serial No. 188,537

7 Claims. (Cl. 15—104.30)

My invention relates to a sewer opener. It has to do, more particularly, with a device which is adapted to be used for dislodging and removing obstructions from sewers or other conduits. However, my device might be used for other purposes.

In the prior art no satisfactory device has been provided for dislodging and removing obstructions from sewers. It is the usual practice in attempting to open clogged sewers, to employ an ordinary cable or wire which is forced into the sewer and by means of which it is attempted to remove the obstruction. Sometimes, the cable or wire is provided with some sort of tool on the end thereof. The cable is necessarily flexible and, consequently, cannot be used successfully as a ramming tool because it is not stiff enough. Also, because of its flexibility it is sometimes difficult to position it in the sewer. Furthermore, the tools provided on the inner end of the cable have not been such that they could be operated to positively grip the obstructing material so that it could be withdrawn from the sewer. There is a need for a device which can be readily inserted in a sewer and which may be used to quickly and efficiently dislodge and remove obstructions therefrom.

One of the objects of my invention is to provide a device for dislodging and removing obstructions from sewers which is of a very simple structure and will be economical to manufacture and which is very efficient for the purposes for which it is intended.

Another object of my invention is to provide a device which is of such a nature that it may be readily positioned in the sewer but which is also of such a nature that it can be successfully used for dislodging the obstructing material and for positively gripping it to remove it from the sewer pipe.

In its preferred form my invention contemplates the provision of a cable having a tool secured to the inner end thereof. This tool may be of such a type that it can be operated to grip the obstructing material in the sewer. On the cable I preferably provide a plurality of loosely mounted balls or beads. These balls or beads are so mounted that they may be moved longitudinally of the cable. On the outer end of the cable I provide a toggle device secured thereto which is adapted to be operated for forcing all of the beads or balls tightly together. This causes the cable to become stiff so that it may be used as a ramming tool. Also, forcing of the beads together is adapted to actuate the gripping tool so that it will grip the obstructing material. The

toggle device is adjustable so that the force tending to keep the beads in contact with each other can be increased or decreased and thereby the stiffness of the device can be varied to meet various conditions.

The preferred embodiment of my invention is illustrated in the accompanying drawings wherein similar characters of reference designate corresponding parts and wherein:

10. Figure 1 is a perspective view of a device made in accordance with my invention.

Figure 2 is a view showing my device positioned in a sewer pipe.

15. Figure 3 is a longitudinal section of the forward part of the device showing a gripping tool and actuating means therefor.

Figure 4 is a detail mainly in section showing how the device may be bent after the beads are forced together.

20. Figure 5 is a side elevation of the toggle device which is adapted to be used to force the beads tightly together.

Figure 6 illustrates a different type of gripping tool which may be mounted on the inner end 25 of the device.

Figure 7 illustrates a still different type of gripping tool.

Figure 8 illustrates another form of gripping tool.

30. Figure 9 shows a bead of a different shape.

Figure 10 shows another toggle device adapted to be positioned at any desired location along the cable.

With reference to the drawings and particularly to Figure 1, I have illustrated my device as comprising a cable 1 upon which a plurality of beads or balls 2 are disposed. These balls are provided with central openings extending therethrough and through which the cable 1 passes.

40. The balls or beads are loosely mounted on the cable so that they may be moved longitudinally of the cable. The balls or beads are preferably made of wood so that they will float. They are preferably treated, for example, by dipping them in paraffine, so that they will be water-resistant and will not become water-soaked. Each of the balls or beads 2 is preferably mainly of spherical form although, as illustrated best in Figure 4, each end of the ball or bead is flattened as indicated at 3.

45. The inner end of the cable 1 preferably has some form of tool secured thereto. This tool may take the form of the gripping tool indicated by the numeral 4 in Figure 1. As illustrated in Figure 3, this gripping tool 4 comprises a plu-

rality of tong members or gripping members 5. These members have their inner ends converging and secured to a cylindrical member 6, as at 7. The outer ends of these members 5 are free and diverge. A frusto-conical sleeve 8 is mounted on the member 6 for movement longitudinally thereof. It will be apparent from Figure 3 that when this member 8 is moved outwardly, the members 5 will be forced towards each other. When the member 8 is moved in the opposite direction, the members 5 will be permitted to move outwardly away from each other. The member 6 is provided with a threaded socket in its outer end which receives a threaded extension 9 projecting from a short cylindrical portion 10. A setscrew 11 may be provided for locking the extension 9 in the threaded socket. The member 10 is adapted to be secured to the inner end of the cable 1, as indicated at 12.

A number of the beads or balls 2 adjacent the gripping tool 4 are provided with metal sleeves or bushings 13 in the central openings provided in the beads. These sleeves 13 are of a sufficient diameter to permit movement of the beads over the cylindrical members 6 and 10. It will be apparent that the innermost bead member will abut the outer end of the sleeve 8. The sleeves 13 will prevent wear on the beads. A compression spring 14 is provided in surrounding relation to the cable 1. The inner end of this spring abuts the outer end of the member 10. The outer end of this spring abuts a bushing 15 provided in a bead disposed adjacent the outer end of the spring. The opening through this particular bead as well as all the other beads from this point outwardly along the cable, is of less diameter than the sleeves 13. The sleeves 13 are of sufficient diameter to permit movement also over the spring 14. When the beads are forced towards the gripping tool, the innermost bead will contact with the sleeve 8 forcing it to the dotted line position illustrated in Figure 3 and thereby operating the gripping tool. At the same time the spring 14 will be compressed by the bead contacting with the outer end thereof. As soon as the pressure tending to force the beads together is released, the spring 14 will force most of the beads in the opposite direction and will permit the gripping members 5 to swing outwardly. The bead with the bushing 15 is so disposed that it will not completely compress the spring 14 against the outer end of member 10 before the gripping tool is actuated.

The means for forcing the bead members tightly together comprises a toggle device 16 secured to the outer end of the cable. This device 16, as illustrated best in Figure 5, comprises a rod 17. This rod 17 has its inner end secured to the cable as at 18. The rod has a sleeve 19 mounted thereon for movement longitudinally relative thereto. This sleeve 19 carries lugs 20 to which is pivotally connected, as at 21, the lower end of a lever and handle member 22. This member 22 is divided at 23 and is provided with a plurality of spaced sets of transverse openings 24. A lever 25 has its upper end projecting into the divided portion 23 of member 22. A bolt 26 is adapted to pass through the openings 24 and an aligning opening in the end of member 25 in order to pivotally connect member 25 to member 22. The point of pivotal connection may be varied by inserting the bolt 26 in either of the sets of openings 24. The opposite end of the lever 25 is pivotally secured at 26a to a cylindrical member 27 threaded on the outer end of the rod 17.

This member 27 is provided with a pair of up-standing lugs 28.

It will be apparent that this structure constitutes a toggle lever mechanism. If the lever 22 is swung downwardly, the sleeve member 19 will be forced inwardly on the rod 17 towards the beads 2. When the member 22 is in its lowermost position, its outer end will be disposed between the lugs 28. A bolt may be passed through aligning openings in these lugs and an opening 29 in the member 22 to lock this member in such position. In order to facilitate holding of the toggle device while member 22 is being swung downwardly, I provide a handle member 30 secured to the member 27. The member 22 is so formed that when it is in its lowermost position, as indicated in Figure 2, it will serve as a crank by means of which the entire device may be rotated. To facilitate holding of the device during this rotation, I provide a handle member 31 which is rotatably carried by a loosely mounted member 2a on the inner end of rod 17.

It will be apparent that when the toggle device is operated, the sleeve 19 will be moved inwardly forcing all of the beads inwardly along the cable and causing all of them to closely abut each other. This will stiffen the cable considerably. Furthermore, it will actuate the gripping tool on the inner end of the cable. The pivotal connection 30 may be adjusted to obtain the required pressure for forcing the beads tightly together. With this adjustment the degree of stiffening produced can be varied to meet various conditions. Due to the fact that the ends of the beads are flattened, as indicated at 3, this will serve to enhance the stiffening action.

In using this device, the toggle device is initially in the position indicated in Figure 1. This will allow all of the beads to be loose on the cable and the entire device will be very flexible. The device may then be passed into the sewer pipe. In passing the device in the pipe, in some instances, it may be desirable to leave it extremely flexible. In other cases it may be desirable to have a small degree of stiffness imparted thereto to facilitate positioning in the pipe. If such is the case, the toggle device may be adjusted to impart a slight degree of stiffness to the cable without operating the gripping tool. In other cases it may be desirable for the device to have its maximum stiffness. In either event, the toggle device may be adjusted to obtain the required stiffness.

The device is usually passed into the sewer pipe until the gripping tool 4 contacts with the obstructing material. Then the toggle device 16 is preferably operated to force the beads tightly together and to actuate the gripping tool. This will cause the device to become very stiff. In this condition it may be used as a ramming device or it may be readily withdrawn to withdraw the tool after it has gripped the obstructing material. As indicated in Figure 4, bending of the cable sufficient to permit removal of the device will be permitted even when the beads are in tight contact. When the cable does bend, as indicated in this figure, since the ends of the beads are flattened as at 3, this will serve to force the beads more tightly into contact with each other. As previously indicated, the beads are preferably of wood. The beads are of sufficient mass that they will cause the entire device to float and will prevent it from dragging along the bottom of the pipe. The device will probably contact with the top of the pipe, as indicated in Figure 2, but if it hits a projection on the top

of the pipe it will readily be forced downwardly into the water. Thus, frictional resistance to movement of the device through the pipe is substantially eliminated. It is possible to have the wood beads of such a mass that the entire device will remain partly submerged and will not contact either with the bottom or the top of the sewer pipe.

It is not necessary to have a gripping tool on the inner end of the device. Some other sort of tool may be provided. In fact, it is not necessary to have any tool at all. The device could be used for ramming obstructions through the pipe and in such case it would not be necessary to have a tool on the inner end thereof. Forcing of the beads into contact with each other makes the device sufficiently stiff so that it could be used as a ramming device.

I may provide a gripping tool of the type illustrated in Figure 6. In this form gripping members 5a are pivotally connected to a cylindrical member 32 as at 33. Springs 34 are provided which contact with the inner ends of members 5a and tend to swing these members so that the outer ends are in their outermost position. The cable 1 passes through a sleeve 35 provided in the member 32. This cable is connected to each of the members 5a as at 36 by means of separate strands 37. With this device, when the beads are forced into contact with each other, the cable 1 will be pulled outwardly relative to the gripping tool. This will cause the members 5a to be swung inwardly about the pivot points 33. Thus, longitudinal movement of the cable relative to the gripping tool, which is produced by forcing the beads into contact with each other, will cause actuation of the gripping tool.

In Figure 7 I show a gripping tool which is the same as that illustrated in Figure 3 with the exception that it is provided with a centrally disposed member 38 similar to a corkscrew. When the device is rotated this member 38 will tend to enter the obstructing material.

In Figure 8 I illustrate another type of tool. This tool is provided with gripping members 5b having their inner ends secured to a sleeve 39. A rod 40 is rotatably mounted in this sleeve. This rod 40 has its outer end secured to the cable 1 as at 41. Stops 42 and 43 are provided on the rod for preventing longitudinal movement of the sleeve on the rod. A sleeve 8b is provided for actuating the gripping members 5b in exactly the same manner that the sleeve 8 actuates gripping members 5. By turning the cable 1, the rod 40 may be rotated relative to the gripping members 5b. The rod may be provided on its outer end with a corkscrew device 44 and cutting blades 45 helically disposed.

It is preferred that the beads 2 be of the shape illustrated in Figure 4. However, they may be of the shape illustrated in Figure 9, where they are not mainly spherical but are mainly cylindrical. Other shapes of beads may be employed. In fact, cylindrical sleeves or collars may be employed, although I prefer the shape illustrated in Figure 4 because such beads will not have a tendency to catch on projections on the sides of the sewer pipe.

In some cases, it may be possible to force only a short length of the device into the sewer pipe because the obstruction is near the point of entrance. In such a case, it is desirable to have an auxiliary toggle device 16a of the type illustrated in Figure 10 which may be mounted on the cable, as indicated by the dotted lines in Figure 1, closely

adjacent the point of entrance into the pipe. This device is practically the same as the device 16 with the exception that it is not provided with the rod 17 and is provided with split collars 19a and 21a rather than members 19 and 21. At the desired point along the cable, the beads may be spread apart sufficiently to permit mounting of this device on the cable. Then when this device is operated the beads will be forced in both directions tightly against each other, stiffening the section of the cable which is in the sewer pipe.

It will be apparent from the above description that I have provided a device having many advantages. The device is simple and is easy to use. It may be rendered extremely flexible or any desired degree of stiffness may be imparted thereto. The gripping tool when used may be readily actuated after it is positioned in the pipe so that it will positively grip the obstructing material. Since the beads are made of wood, the entire device will float in the water in the pipe. This will reduce the frictional resistance to movement of the device through the pipe. Although the device will be stiff after the beads are forced into contact with each other, sufficient bending will be permitted to facilitate removal of the obstructions from the pipe. The beads are so shaped that they will not tend to catch on anything on the sides of the pipe. The toggle device is of such a nature that it may be locked in position to hold the beads in firm contact with each other. Furthermore, the toggle device may be adjusted to vary the pressure produced on the beads.

Many other advantages will be apparent from the preceding description, the drawings and the following claims.

Having thus described my invention, what I claim is:

1. A device of the type described comprising a cable, a gripping tool secured to one end of said cable and embodying a plurality of movable gripping members, means for stiffening said cable and simultaneously moving said gripping members into operative position, said means comprising a plurality of members surrounding said cable and adapted to be moved longitudinally thereof, means for forcing said members tightly into contact with each other, and springs for forcing said gripping members into inoperative position as soon as said last-named means is rendered inoperative.

2. A device of the type described comprising a flexible cable, a gripping member on the end of said cable, a multiplicity of units carried by said cable, and means for crowding said units together to render the cable stiff and for actuating said gripping device.

3. A device of the type described comprising a cable, a gripping tool secured to one end of the cable and adapted to be actuated by pressure applied to the inner end thereof, a plurality of members mounted on said cable for movement longitudinally relative thereto, and means for forcing said members tightly into contact with each other and for moving them relative to said cable to actuate said gripping tool by pressure transmitted by said members along the cable and to said inner end of the gripping tool.

4. A device of the type described comprising a cable, a gripping tool secured to one end of the cable and adapted to be actuated by pressure applied to the inner end thereof, a plurality of members mounted on said cable for movement longitudinally relative thereto, and means for forcing said members tightly into contact with each other

and for moving them relative to said cable to actuate said gripping tool by pressure transmitted by said members along the cable and to said inner end of the gripping tool, said means being adjustable to vary the pressure of contact between said members.

5. A device of the type described comprising a cable, a gripping tool secured to one end of the cable and adapted to be actuated by pressure applied to the inner end thereof, a plurality of bead members mounted on said cable for movement longitudinally relative thereto, and means for forcing said bead members tightly into contact with each other and for moving them relative to said cable to actuate said gripping tool by 15 pressure transmitted by said members along the cable and to said inner end of the gripping tool and to simultaneously stiffen the cable.

6. A device of the type described comprising a cable, a gripping tool secured to one end of the cable and adapted to be actuated by pressure applied to the inner end thereof, a plurality of bead members mounted on said cable for movement

longitudinally relative thereto, and a toggle device secured to said cable for forcing said bead members tightly into contact with each other and for moving them relative to said cable to actuate said gripping tool by pressure transmitted by said members along the cable and to said inner end of the gripping tool and to simultaneously stiffen the cable.

10 7. A device of the type described comprising a cable, a gripping tool secured to one end of the cable and adapted to be actuated by pressure applied to the inner end thereof, a plurality of bead members mounted on said cable for movement longitudinally relative thereto, and a toggle device secured to said cable for forcing said bead members tightly into contact with each other and for moving them relative to said cable to actuate said gripping tool by pressure transmitted by said members along the cable and to said inner end of the gripping tool and to simultaneously stiffen the cable, said toggle device being adjustable to vary the pressure produced thereby.

LEWIS G. MCKENZIE.
